UNITED STATES PATENT OFFICE.

RALPH R. RICHARDSON, OF CHICAGO, ILLINOIS, ASSIGNOR TO CHICAGO CARTON COMPANY, OF CHICAGO, ILLINOIS, A CORPORATION.

DISPLAY STRUCTURE AND CARTON THEREFOR.

1,104,933.

Specification of Letters Patent. Patented July 28, 1914.

Application filed March 20, 1911. Serial No. 615,800.

To all whom it may concern:

Be it known that I, RALPH R. RICHARDSON, a citizen of the United States, and a resident of Chicago, county of Cook, and 5 State of Illinois, have invented certain new and useful Improvements in Display Structures and Cartons Therefor, of which the following is a full, clear, and exact description.

10 In advertising goods that are sold in packages or cartons, the cartons or large sized replica of the same are frequently displayed in fanciful built-up arrangements or structures in store windows or the like. In such 15 built-up arrangements, the cartons are usually connected by wire staples or other similar fastening means.

The present invention relates to such display structures and cartons and seeks to provide 20 a simple and improved construction by which the cartons can be connected together in various ways without the use of staples or the like for forming built-up displays.

The invention consists in the features of 25 improvement hereinafter set forth, illustrated in the preferred form in the accompanying drawing and more particularly pointed out in the appended claims.

In the drawing, two of the improved cartons are shown connected together and Figure 1 is a longitudinal section of the two connected cartons on the lines 1—1 of Figs. 2 and 3. Fig. 2 is a top view of the two connected cartons and Fig. 3 is a bottom view 35 thereof with the outer flaps of one of the cartons opened to show the manner of connecting the cartons at their lower ends.

The improved display carton is preferably collapsible and is formed in the well-known 40 manner of a single sheet or blank of paper board, the blank being cut at its ends to form the pairs of folding flaps *a* and *a'* and *b* and *b'*. The blank is also scored, as usual, to form the longitudinal folds between the 45 sides *c* and the transverse folds between the sides and the folding end flaps. The side edges of the blank are overlapped and glued or cemented, as indicated at *c*, to hold the carton in shape when it is expanded and the 50 end flaps folded. The pair of opposite flaps *b* and *b'* constitute what may properly be termed the "inner" flaps and the pair of opposite flaps *a* and *a'* constitute the "outer" flaps. In ordinary use, the carton is filled 55 with goods and the inner flaps *b* and *b'* are

first folded inwardly upon the goods. The outer flaps are then folded inwardly over the inner flaps. The flap *a* is provided at its outer edge with laterally projecting tongues 1 which are adapted to interlock with two 60 inclined slits 2, formed in the opposite outer flap *a'*, near the outer edge thereof. The outer flaps are thus arranged and adapted to be folded inwardly and the tongues and grooves thereof interlock to close the end of 65 the package.

In the ordinary carton, the inner pair of opposite flaps are not provided with tongues and slits, but in cartons with the present invention, one of these inner flaps *b* is provided adjacent its outer edge with a pair of laterally extending tongues 3 and the opposite inner flap *b'* is provided with a pair of inclined slits 4 adjacent its inner edge. The 70 tongues 3 and slits 4 of the flaps of any one carton are not adapted to interlock when these flaps are folded inwardly in the ordinary manner, but by turning these flaps outwardly, they can be connected to the inner flaps of similar cartons by interlocking the 75 tongues 3 of the flap *b* of one carton with the slits 4 of the flap *b'* of another similar carton. As shown in the drawing, the flap *b* at the upper end of the carton A is connected to the flap *b'* at the upper end of a similar 80 carton A' by interlocking the tongues 3 and slits 4 of these flaps. These tongues and slits are so arranged that when interlocked, the ends of the adjacent cartons are held apart in offset relation. It is obvious that 85 the flap *b'* at the upper end of the carton A and the flap *b* at the upper end of the carton A' can be connected in the same way with other similar display cartons, and at the same time the ends of the connected cartons 90 can be closed by interlocking the tongues 1 and slits 2 of the other pair of flaps *a* and *a'* of each carton, as shown in Figs. 1 and 2.

In the form shown, the flap *b* is also provided near its inner or hinged edge with an 100 inwardly projecting tongue 5 and the opposite inner flap *b'* is provided adjacent its inner or hinged edge with a transverse slit 6. This tongue and slit of the inner flaps of the same carton cannot be interlocked, but 105 the inner flap *b* of one carton can be connected to the inner flap *b'* of another similar carton by interlocking the tongue 5 and slit 6 of these flaps. As shown in the drawing, the inner flap *b* at the lower end of the 110

carton A' is outturned and is connected to the inner flap b' of the carton A by interlocking the tongue 5 and slit 6 of these flaps. The flaps thus interlocked are turned inwardly into one of the other of the connected cartons before the end of the carton is closed. As shown in Figs. 1 and 3, these connected flaps of the two adjacent cartons are turned into the carton A before its lower end is closed by the opposite outer flaps a and a'. In Fig. 3 the outer flaps a and a' are turned outwardly to show the manner of connecting the flaps b and b' of the two adjacent cartons. When the flaps b and b' of two adjacent cartons are connected by the tongue 5 and slit 6 of the flaps b and b', the ends of the connected cartons are held closely adjacent, as clearly shown in Fig. 1. It is obvious that the flap b of the carton A and the flap b' of the carton A' may be utilized to connect these cartons in the same manner to other similar cartons.

By utilizing the inner flaps to connect a number of cartons in offset relation at one end and in close adjacent relation at the other end, an arch or a complete circle of cartons may be formed. It is obvious that the inner flaps b and b' at the opposite ends of the cartons can be utilized to connect the cartons either with the upper ends in offset relation and the lower ends in adjacent relation, or to connect both the upper and lower ends either in offset or adjacent relation. If both the upper and lower ends are connected either in offset or adjacent relation, a straight row of connected cartons may be formed and such a row can serve to form a column or transverse beam in building up the fanciful arrangement or display of cartons. In this way the displayed cartons can be connected together and built up in different fanciful arrangements.

It is obvious that changes may be made in the details set forth without the departure from the essentials of the invention as defined in the claims.

I claim as my invention:—

1. A display structure comprising two or more cartons each provided with outer and inner folding flaps at its end, the outer

pair of opposite flaps of each carton having tongues and slits arranged to interlock and connect said flaps and close the ends of the carton, one flap of each of the inner pairs having tongues adjacent the outer free edge, the other having slits adjacent its hinged edge and a tongue adjacent the hinge and edge of one of said inner flaps and a slit adjacent with inner edge of the other inner flap, specifically as described. 60

2. A collapsible display carton having side walls and pairs of outer and inner folding end flaps a, a' and b, b', said outer pairs of flaps a, a' having interlocking tongues and slits 1 and 2 adapted to interlock to 65 connect the flaps and close the end of the carton, one of said inner flaps b having interlocking tongues 3 and 5 adjacent both its outer free edge and its inner hinged edge and the other of said inner flaps b' having slits 4 and 6 adjacent its inner hinged edge, said tongues 3 being arranged to interlock with the slits 4 of the flaps of similar cartons to connect the same in offset relation and said tongue 5 being arranged to interlock with the slit 6 of the flaps of similar cartons to connect the same in adjacent relation, substantially as described. 70

3. A display structure built up of individual cartons each having flaps interlocked to close its ends and each having other flaps interlocked with the corresponding flaps of the adjacent carton to thereby connect the individual cartons of the structure, substantially as described. 80

4. A display structure built up of individual cartons each having two pairs of opposite flaps at its ends provided with interlocking tongues and slits, one of the pairs of flaps at each end of the carton being 90 interlocked to close the ends of the cartons, the other flaps of adjacent cartons being interlocked to connect the individual cartons into a display structure, substantially as described.

RALPH R. RICHARDSON.
